UNITED STATES PATENT OFFICE.

ALEXANDER BRADY, OF NEWTON LOWER FALLS, MASSACHUSETTS, ASSIGNOR TO NEW ENGLAND CONFECTIONERY COMPANY, OF BOSTON, MASSACHUSETTS, A CORPORATION OF MASSACHUSETTS.

DUMPING-MACHINE.

1,253,664.

Specification of Letters Patent. Patented Jan. 15, 1918.

Application filed May 19, 1916. Serial No. 98,678.

To all whom it may concern:

Be it known that I, ALEXANDER BRADY, a citizen of the United States, and a resident of Newton Lower Falls, in the county of 5 Middlesex and Commonwealth of Massachusetts, have invented an Improvement in Dumping-Machines, of which the following description, in connection with the accompanying drawings, is a specification, like 10 characters on the drawings representing like parts.

This invention relates to machines for dumping candy wafers and other articles, and is an improvement upon the machine 15 shown in my copending application Serial No. 739,698, filed January 2, 1913.

In the course of the manufacture of the candy wafers they are placed upon boards or shallow trays to dry and then discharged 20 from the trays in readiness to be wrapped. The present machine enables an assembly of trays to be manipulated as a unit simultaneously to discharge the wafers therefrom, while reducing the amount of breakage of 25 wafers to a minimum.

The character of the invention may be best understood by reference to the following description of an embodiment thereof shown in the accompanying drawings, 30 wherein:—

Figure 1 is a side elevation of the dumping machine shown herein as embodying the invention;

Fig. 2 is a rear elevation of the machine; 35 Fig. 3 is a vertical section through the carrier showing the same in upright position;

Fig. 4 is a vertical section through the carrier and its counterbalancing means showing parts in discharging position; and 40 Fig. 5, on an enlarged scale, is a horizontal section through a portion of the carrier.

Referring to the drawings, the machine shown therein as embodying the invention 45 comprises a frame having uprights 1 on which is journaled a horizontal shaft 3 projecting through and serving as a fulcrum for a box-like carrier 5 comprising a bottom 7, a top 9 and side walls 11. The front end 50 of the carrier is open and adapted to receive a truck 13 loaded with an assembly of superposed trays 15 containing the wafers. The carrier may be formed to conform to the assembly of trays and thereby contribute to 55 the holding thereof in proper assembled re-

lation. The frame may be mounted on a floor 17 having a recess 19 therein to receive the bottom of the carrier with the upper surface thereof flush with the floor to facilitate the rolling of the truck into and out of 60 the carrier.

To normally hold the carrier in its upright position it is provided with a spring latch 21 adapted to engage a block 23 on the floor. To release the latch a lever 25 65 (Fig. 2) is pivoted on said block and is urged against a stop 27 by a spring 29. This lever is extended beyond the frame to present a treadle 31 which when depressed will release the latch as desired. 70

To manipulate or tilt the frame and the assembly of trays therein as a unit, to slide the wafers along the trays, ropes 33 or other flexible members may be connected to the carrier at points 34, and extend up over 75 pulleys 35 and thence downward to drums 37 fast on the shaft 3 referred to, which has a crank 39 fast thereon.

When the crank is rotated it will wind the ropes on the drums and thereby tilt the carrier in a contra-clockwise direction from its position shown in Fig. 3 until the points 34 of connection of the cable with the carrier are directly above the axes of the drums. The momentum of the movement of 85 the carrier will cause said points to swing beyond this position and then the handle is rotated gradually, slightly in the opposite direction to allow the carrier to swing somewhat farther in a contra-clockwise direction 90 to its position shown in Fig. 4.

To counterbalance the carrier and facilitate the tilting thereof, a rope or other flexible member 41 may be connected to the top of the carrier and pass over a fixed pulley 95 43 to a weight 45 adapted to slide in a well 47.

The weight is designed to counterbalance the carrier when loaded with a truck and trays and consequently will outbalance the 100 carrier when empty. Therefore if the latch 21 is inadvertently released the weight is liable to tilt the carrier with a sharp, quick movement and injure any operative within range thereof. To prevent any possibility 105 of this, the weight is locked at the top of the well excepting when the handle is operated to tilt the carrier. To this end a latch 49 is pivoted to the well 47 and provided with a toe 51 adapted to project through a 110

hole 53 in the wall of the well beneath the weight. The latch is connected to a rope 55 or other flexible member extending up over a pulley 57 on the frame and thence down to a short arm 59 fast on the end of the horizontal shaft 3 opposite the handle.

Thus on the initial rotation of the handle the rope 55 will be pulled downward and rock the latch outward and release the weight and render the same effective to counterbalance the carrier. The continued rotation of the shaft to complete the tilting of the carrier will wind the rope 55 thereon and rock the latch on outward to its position shown in Fig. 4. When the handle is turned to return the carrier to its upright position the latch will gradually rock downward, and after the weight reaches the upper end of the well, will project beneath the same as shown in Fig. 1.

In the machine shown in my said copending application, the carrier is provided with a fixed wall located a considerable distance from the delivery ends of the trays to form a chamber sufficiently large to receive the contents of the trays and permit the same to slide along the wall and discharge from the carrier. In dropping through this considerable space between the trays and the fixed wall many of the wafers were liable to be broken.

An important feature of the invention relates to means for preventing this breakage. To accomplish this the carrier is provided with a wall 61 adapted to receive the wafers from the trays and move gradually away therefrom to allow the wafers to slide along said wall and discharge from the carrier. To shift the wall toward and from the trays, leaves 63 may be provided extending the length of the carrier and hinged to upper and lower cross members 65 and an intermediate cross member 67 on the frame. These leaves are folded back against said members to permit the wall to move away from said trays and are folded into positions perpendicular to said members to shift the wall back toward the trays. To control the leaves in this manner they are provided with arms 69 fast thereon, connected by links 71 with a lever 73 fulcrumed intermediate its ends on the member 67. To shift the lever to move the wall toward the trays, a spring 75 is provided having one end connected to said lever and its opposite end anchored to the cross member 67. Movement of the lever by the spring is limited by a stop 77 on said cross member.

To shift the lever to permit the wall to move away from said trays, a rope 79 or other flexible member may have one end connected to said lever and extend thence through a guide eye 81 on the carrier and have its opposite end anchored to an eye 83 on the frame. This rope has sufficient slack

so that it will be ineffective to shift the lever until the carrier approaches the limit of its tilting movement to discharge. On the occurrence of this event the rope 79 will be tightened to shift the lever 73 in a clockwise direction (Fig. 2), thereby gradually rocking said leaves from their full line positions shown in Fig. 5 to their dotted line positions shown in said figure. The weight of the wall or the wafers thereon will cause the wall to follow the leaves and thereby move gradually away from the trays and lower the wafers therefrom gently and without liability of breakage.

The wafers on the wall are adapted to slide along the same to a gate 85 (Fig. 4) hinged on the carrier adjacent one end of said wall. To automatically operate the gate it is connected to a rope 87 or other suitable flexible connection which is guided over a pulley 89 mounted on the carrier and connected to a weight 91 adapted to slide in a pocket 93 of the carrier.

When the carrier is in its upright position the weight will gravitate to the bottom of its pocket and hold the gate closed as shown in Fig. 1. But when the carrier is tilted to its discharging position the weight will slide to the opposite end of its pocket and allow the gate to open and permit the wafers to slide along the wall therefrom.

Preferably the wall should be spaced somewhat from the edges of the trays to furnish a chamber of sufficient size to accommodate the wafers as they slide from the trays on the tilting of the carrier and before the movement of the wall away from the trays. To provide such a chamber, a frame 95 may be introduced into the carrier and serve as an abutment to receive the inner ends of the trays and hold them spaced from the rear end of the carrier. Thus when the carrier is tilted to discharging position, the wafers will slide into this chamber against the wall 61, but the chamber is so shallow that the wafers will not drop a sufficient distance to break them.

To check the sliding of the wafers along said wall before it is moved away from the edges of the trays, a series of partitions 97 may be introduced into said chamber and hinged to said frame. They are free to swing in one direction, but are limited by stops 99 on the frame from swinging in the opposite direction. As a result the partitions will be properly held to check the sliding of the wafers along the wall during the first part of the tilting of the carrier, but will be free to swing to their positions shown in Fig. 4 to facilitate the discharge of the wafers during the latter part of the tilting of the carrier and when the wall is being moved gradually away from the edges of the trays.

Having described one illustrative embodi-

ment of the invention without limiting the same thereto, what I claim as new and desire to secure by Letters Patent is:—

1. A machine for dumping articles comprising in combination a carrier for an assembly of trays for receiving the articles, a wall, means to tilt said carrier to slide the articles along said trays against said wall, and means to rectilinearly move said wall away from said trays to allow the articles to slide along said wall from the carrier.

2. A machine for dumping articles comprising in combination a carrier for an assembly of trays for receiving the articles, a wall, means to tilt said carrier to slide the articles along said trays against said wall, and means automatically to move said wall rectilinearly away from said trays to discharge the articles.

3. A machine for dumping articles comprising in combination a carrier for an assembly of trays for receiving the articles, means to tilt said carrier and trays as a unit to slide the articles along said trays, means to receive the articles from said trays, and means rectilinearly gradually to move said receiving means from said trays to discharge the articles.

4. A machine for dumping articles comprising in combination a carrier for an assembly of trays for receiving the articles, means to manipulate said carrier and trays as a unit to slide the articles along said trays, and a rectilinearly movable wall to receive and gradually lower the articles from said trays as said carrier approaches discharging position.

5. A machine for dumping articles comprising in combination a carrier for an assembly of trays for receiving the articles, means to manipulate said carrier and trays as a unit to slide the articles along said trays, means to receive said articles from said trays, and means automatically and rectilinearly to move said receiving means away from said trays in the course of the said manipulation thereof.

6. A machine for dumping articles comprising in combination a carrier for an assembly of trays for receiving the articles, a wall, means to tilt said carrier to slide the articles along said trays against said wall, partition means between said trays and wall, and means rectilinearly to move said wall from said partition means to allow discharge of the articles.

7. A machine for dumping articles comprising in combination a carrier for an assembly of trays for receiving the articles, means to tilt said carrier and trays as a unit to slide the articles along said trays, a wall, partition means between said wall and trays, and means to move said wall away from said trays to allow discharge of the articles, said partition means having

provision permitting the same to swing to facilitate the discharge of the articles.

8. A machine for dumping articles comprising in combination a carrier for an assembly of trays for receiving the articles, means to tilt said carrier to slide the articles along said trays, a wall, means to move said wall away from said trays, partition means between said wall and trays adapted to swing in one direction, and stop means to limit movement thereof in the opposite direction.

9. A machine for dumping articles comprising in combination a carrier for an assembly of trays for receiving the articles, means to manipulate said carrier and trays as a unit to slide the articles along said trays, a wall to receive the articles, and means for shifting said wall including elements hinged on said carrier, arms projecting from said elements, a lever fulcrumed on said carrier, links connecting said arms with said lever, a stop, spring means tending to swing said lever against said stop, and a flexible member having a fixed end and one end connected to said lever.

10. A machine for dumping articles comprising in combination a carrier for an assembly of trays for receiving the articles, means to manipulate said carrier to slide the articles along said trays, and discharging means for said carrier including a wall, elements for engagement with said wall, and means for actuating said elements to shift said wall rectilinearly relatively to said trays.

11. A machine for dumping articles comprising in combination a carrier for an assembly of trays for receiving the articles, means to manipulate said carrier to slide the articles along said trays, a wall, elements hinged on said carrier to engage the rear face of said wall, and means to rock said elements to shift said wall relatively to said trays.

12. A machine for dumping articles comprising in combination a carrier for an assembly of trays for receiving the articles, means to manipulate said carrier to slide the articles along said trays, a wall adjacent ends of said trays, leaves on the carrier at one side of said wall, and means to move said leaves to shift said wall relatively to said trays.

13. A machine for dumping articles comprising in combination a carrier for an assembly of trays for receiving the articles, means to manipulate said carrier to slide the articles along said trays, a wall adjacent ends of said trays, and means to shift said wall relatively to said trays including a hinged element, a lever connected thereto, means tending to shift said lever in one direction, and means for automatically shifting said lever in the opposite direction.

14. A machine for dumping articles comprising in combination a carrier for an assembly of trays for receiving the articles, means to manipulate said carrier to slide the articles along said trays, a wall to receive the articles from said trays, and means to move said wall rectilinearly away from said trays at a predetermined point in the manipulation of the carrier.
15. A machine for dumping articles comprising in combination a frame, a carrier fulcrumed thereon for receiving an assembly of trays for receiving articles, means to tilt said carrier, a wall to receive articles from said trays, and means including a member connected to said frame and carrier for automatically shifting said wall from said trays in the course of the tilting of the carrier.
16. A machine for dumping articles comprising in combination a carrier for an assembly of trays, means to tilt the carrier, counterbalance means for the carrier, latch means to hold the carrier in its upright position, and latch means coöperating with said counterbalance means to prevent the latter from tilting the carrier on inadvertent release of said carrier-latch means.
17. A machine for dumping articles comprising in combination a frame, a carrier fulcrumed thereon, a counterbalance weight for said carrier, a flexible member connecting said carrier and weight, a well for receiving said weight, and latch means mounted on said well for controlling said weight.

In testimony whereof, I have signed my name to this specification.

ALEXANDER BRADY.
